ROUTING MACHINE

Albert E. Schnable, Ocean Grove, N. J.

Application October 4, 1941, Serial No. 413,701

11 Claims. (Cl. 90—13.1)

This invention relates to what is commonly referred to as routing machines, particularly machines of this type and kind designed to reproduce various forms and kinds of printing material, such as type, cuts, or printing workpieces of any kind for the purpose of reproducing the same or to produce reductions or enlargements thereof.

The object of the invention is to provide a machine of the class defined which is constructed in such manner as to produce accurate reproductions of a pattern in a workpiece, the latter being preferably in the form of a zinc plate, and in firmly guiding and supporting the tracer stylus and the routing tool in the operation of the machine, a further object being to provide foot actuated means in combination with hand actuated means for actuating the pantograph employed for supporting and guiding the stylus and tool in a predetermined ratio, one with respect to the other, in producing the finished workpiece, product or matrix; a further object being to provide means for regulating the depth of cut formed by the tool in the workpiece; a further object being to provide a tool supporting chuck having means providing free rotation of the tool therein and for circulating air through the tool to provide extremely high speed operation of the tool and eliminate overheating thereof; and with these and other objects in view, the invention consists in a machine of the class and for the purpose specified which is simple in construction, efficient in use and which is constructed as hereinafter more fully described.

The invention as fully disclosed in the following specification of which the accompanying drawings form a part, in which several parts of my invention are indicated by suitable reference characters in each of the views, and in which:

Fig. 1 is a side view of a machine made according to my invention.

Fig. 2 is a sectional plane view substantially on the line 2—2 of Fig. 1.

Fig. 3 is an enlarged detailed sectional view on the line 3—3 of Fig. 1.

Fig. 4 is an enlarged plane view of a part of the table portion of the machine showing the type or pattern supporting means of the machine.

Fig. 5 is a partial section on the line 5—5 of Fig. 4.

Fig. 6 is a partial section on the line 6—6 of Fig. 5.

Fig. 7 is a partial section on the line 7—7 of Fig. 2 on an enlarged scale.

Fig. 8 is a vertical sectional view through the stylus holder, which I employ.

Fig. 9 is a section on the line 9—9 of Fig. 7.

Fig. 10 is a sectional detailed view through the 55

mounting end of one of the handled members, which I employ.

Fig. 11 is a section on the line 11—11 of Fig. 7.

Fig. 12 is a side view of the tool supporting chuck arranged in its support with part of the construction broken away and in sections.

Fig. 13 is a vertical sectional view through the tool supporting chuck showing parts of the construction broken away and in sections.

Fig. 14 is a cross section on the line 14—14 of Fig. 13.

While routing machines are old in the arts, generally speaking, and while efforts have been made in the past to produce routing machines for reproducing type or other kinds of printed matter, particularly in making enlargements or reductions thereof, machines of the later type and kind have not been put into commercial use by reason of the inability of such machines to produce accurate results in the finished workpiece or matrix; part of the difficulties have been in the construction of the machine, generally speaking, to make the machines practical in use and more particularly machines of this type and kind have been impractical from the standpoint of a proper mounting and means for actuating the routing tool employed.

I have overcome objectionable features to machines of the type and kind under consideration by providing a simple and sturdy design of machine having substantially frictionless supports for the various operating elements of the machine, particularly the stylus and the workpiece, while at the same time producing a machine wherein the mounting of the pantograph arms, type or pattern and the workpiece may be quickly adjusted in the machine, as well as, in coupling and uncoupling the same with respect thereto. Still further means is provided to produce a substantially frictionless rotatable mounting of the tool in the chuck body and for circulating air through the chuck body to prevent overheating thereof, thus providing for the high speed operation of the tool.

The operation of my improved machine is further simplified by including foot actuated means for positively operating the pantograph mechanism in two directions, thereby minimizing the hand operation of the stylus over the type or pattern member, as well as, the movement of the routing tool with respect to the workpiece or stylus.

In the accompanying drawings, I have illustrated one adaptation of the machine, in Fig. 1, 15 is the standard of the frame of the machine to the top of which is secured a table 16 having a transverse recess 17 in the upper surface thereof;

the forward wall 18 of which is bevelled and the rear wall 19 of which is perpendicular.

Supported upon the upper rear portion of the standard 15 in a suitable bracket or housing 20, is an electric motor 21, on the shaft of which is a pulley 22, around which passes a belt 23. Extending vertically from the bracket or housing portion 20, is an upstanding tubular column 24. Clamped to the column 24 is a stub shaft 25 carrying a pulley 26 around which the belt 23 passes. Also on the shaft 25 is another pulley 27 around which passes a belt 28, which in turn passes around a pulley 29 on a shaft 30, supported in a tubular cross-head 31, the latter being vertically adjustable in the top of the column 24 by an eccentric 32 rotated through the medium of a hand wheel 33 to raise and lower the cross-head. The cross-head is clamped in different positions of adjustment by a bolt 34 operating in elongated slots 35 formed in a depending sleeve 36 of said cross-head.

At 37 is shown any suitable type or kind of flexible shaft construction having means, as at 38, for coupling the same with the drive shaft 30 and means, as at 39, for coupling the other end of the shaft with a tool supporting chuck or spindle housing 40, the spindle end of the flexible shaft protruding into the chuck 40 as seen at 41.

An adjustable nut 24a and split clamp ring 24b controls vertical adjustment of the column to tighten the drive belt 23, and the belt 28 is tightened by adjustment of the cross-head 31, in the column. On the table of the machine, is supported a pantograph linkage 42 comprising, in the construction shown, four arms 43, 44, 45 and 46. Suitable means is provided at 47 to adjustably couple the arms 43, 45, and 44, 46 to increase or decrease the ratio of movement between chuck 40 mounted on the end of the arm 46 and a stylus 48, supported in a stylus holder 49 mounted on adjacent pivoted ends of the arms, 44-45. The arm 43 is adjustably pivoted upon the table 16 being adjustably clamped in a slotted plate 50 which plate is arranged in the recess 17 of the table and retained in different positions of adjustment longitudinally of said recess by retaining wedge blocks 51. The other ends of the arms 43-46 are pivotedly coupled as seen at 52 and the pivot coupling comprises a tubular casing 53, the lower contracted end of which supports a bearing ball 54 which operates over a smooth sheet 55 upon the rear portion of the table 16. This later construction provides free movement of the pantograph mechanism, or at least the arms of this mechanism, over the table of the machine and in conjunction with other guides and supports later described, maintains this mechanism in substantially horizontal position.

Coupled with the housing 53, is a swivelled link 56 which in turn is pivoted to a link arm 57 extending upwardly from one end of a rocker shaft 58 supported in bearings 59 at one side of the table of the machine. The other end of the rocker shaft 58 has a depending link arm 60, to which is pivoted a long link 61, the other end of the link 61 being pivoted to a link 62. Another link arm 63 is arranged on the shaft of the arm 62 and is pivoted to a depending link 64, pivoted at its lower end to a foot treadle 65. The treadle 65 is pivoted centrally as seen at 66 to a forwardly extending bracket 67 at the base of the standard 15. It will thus be seen that by actuating the treadle to raise or lower

the inner end thereof, by heel and toe pressure applied to the treadle, the arms of the pantograph mechanism may be moved transversely across the surface of the table. In this way, the hand operation of the stylus and tool, as later described is materially relieved.

Substantially centrally of the table is adjustably supported a dish-like plate 68 held in different positions of adjustment longitudinally of the recess 17 by wedge blocks 69 similar to the blocks 51. The upper surface of the plate 68 has a large recess 70, the bottom wall of which is provided with elongated apertures 71, to guide a clamp bar 72 in its movement toward and from a block of type 73, or any other kind of pattern to be traced. Vertically adjustable in the bar 72 is a threaded segment 74, note Fig. 4, movable into and out of engagement with a feed screw 75, providing quick, as well as, slow adjustment of the bar 72.

By actuating the mill nut 76, the segment 74 may be raised out of engagement with the screw 75, in providing quick sliding of the bar 72, whereas when the segment 74 is in engagement with the screw 75, the bar 72 may be adjusted by rotating the knob 77, which in turn rotates a pinion 78 meshing with another pinion 79 on one end of the screw 75.

Slidably mounted in the recess 70 of the plate 68, is a backing bar 80 held against displacement by a screw 81, which operates in an elongated recess 82 in the bar to provide for the adjustment of said bar through the medium of a feed screw 83. The screw 83 is operated through a knurled knob 84 mounted in one side of the plate 68 and on the shaft of this knob is a gear 85, meshing with the corresponding gear 86 on one end of the screw 83. (Note Figs. 4 and 5.)

I may also use in conjunction with the type 40 73 shims or spacing members 87 to position the type characters 88 comprising the letters MAY, in the plate 68. It will, of course, be apparent that the members 87 may be arranged at either side of the type 73 and may be of varying dimensions 45 similar to the use of slugs or leads in alining type in a chase or form.

With the plate structure 68 disclosed, it will be apparent that the type or other pattern element 73 may be adjusted to any desired position within the recess 70, by adjustment of the two bars 72 and 80 and by using one or more of the members 87.

Arranged at one side of the plate 68 is a workpiece supporting plate 89 also fitting in the recess 17 and retained in different positions of adjustment in the recess by wedge blocks 90. The plate 89 has a recess 91 which corresponds in depth to the recess 70, that is to say, is type high particularly when the invention is used for the reproduction of type and other printing elements. The recess 91 is bounded on one side of the plate by a wall 92, note Fig. 2, which has a T-slot, therein to receive clips, such as the clips 93 adjustably clamped in T-slots 94 formed in the upper surfaces of the front and rear walls of the plate, as clearly seen in Figs. 2 and 7. Clips are employed in the slotted wall 92 when a large workpiece is supported in the recess 91. In the present showing, a relatively small workpiece 95 is illustrated as supported in the plate 89 and retained in adjusted position by the clips 93.

In the construction shown, the workpiece 95 is composed of a top zinc or other metallic plate 96 backed by one or more wood or other known metallic backings 97. At this time, it will be well

to point out that in routing the workpiece to form the reproduction of the type or other pattern, the height of the reproduction as formed in the workpiece may be varied by controlling the depth of routing and this is independent of other modification which might be made in the reproduction of the pattern, that is to say, to increase or decrease the size thereof. In some instances, the routing may extend into the wood in producing the resulting product or matrix.

Arranged upon and longitudinally of the front portion of the table is a freely rotatable supporting tube 98, the ends of which are arranged in suitable brackets 99. The tube provides a more or less frictionless bearing for the operating handles 100, both of which are of the same construction and one of which is coupled with the stylus supporting body 49, and the other with the chuck body 40.

As both handle members 100 are of the same construction the brief description of one is applied to both. Each handle member comprises a tube 101, note Fig. 10, and in the inner end of the tube is secured an elongated bushing 102 forming a sliding bearing for the pin or rod portion 103 of a coupling 104. The coupling 104 is flanged beyond the limits of the tube 101 to fit corresponding enlarged casing portions 105 arranged on the members 40 and 49 and forming part of the pivot ends of the arms 44 and 46, one of the casing portions 105 being illustrated in Fig. 12 of the drawings. The coupling 104 also includes a pin like bearing 106, which extends into the casing 105 to reinforce the attachment of the handle therewith, the couplings 104 being secured to the casings 105 by screws 107, which are illustrated in Fig. 2 of the drawings.

The pin or rod 103 is arranged eccentrically in the bearing 102, note Fig. 11, and arranged concentrically around the axis of the pin 103 on the flanged portion of the coupling are circumferentially spaced apertures 108, in one of which a pin 109 secured in the end of the bushing 102 is adapted to be placed. The handle member 101 is held in abutting relationship to the coupling 104 by spring 110 arranged on the pin 103 and the tension of which is controlled by an adjustment nut 111. In other words, the spring 110 holds the handle in operative keyed position with the coupling. However, the handle may be moved outwardly against the tension of the spring 110 to place the pin 109 in another of the apertures 108. With this construction, I provide means for vertically adjusting the position of the members 40 and 49 independent of the adjustable mounting of the tool elements with respect to said members.

The chuck 40 comprises an elongated casing 112 having an upper enlarged and circumferentially ribbed end 113, which forms a hand grip portion on the chuck. Arranged in the casing, in self-aligning ball bearings 114 and 115, is a spindle 116. The upper end of this spindle has a recess 117 to receive the flexible shaft coupling 41, a key pin 118 being arranged in the spindle to engage a flat side 119 on the end 41 to key the shaft with the spindle. The upper end of the spindle is threaded to receive a retaining nut 120 which bears against the bearing 114 and this threaded engagement is preferably made by a left-hand thread structure. Another retaining nut 121 is mounted in the lower end of the casing 112 and this nut is also preferably provided with the left-hand thread.

Arranged upon the spindle 116 between the bearings 114 and 115 and frictionally engaging

the spindle is an elongated circumferentially ribbed sleeve forming a fan 122. The ribs or blades 123 of the fan are mounted for free rotation in the bore of the casing 112. This fan is employed to circulate air through the casing, circulating ports being provided in the head 113, as seen at 124 and a clearance is provided as at 125 between the retaining nut 121 and a clamp nut 126 arranged upon the lower split and bevelled chuck end 127 of the spindle.

The chuck end 127 of the spindle has an elongated tool receiving aperture to receive the shank 128 of a routing or other tool 129. It is also preferred, that the nut 126 be provided with a series of radial, as well as, angularly disposed fan blades 130 which are employed to circulate air at the base of the chuck and around the tool to aid in the cooling properties, while at the same time, to remove particles out from the workpiece. Secured in the top enlarged portion 113 of the casing, is a milled nut 131 which fits freely around the upper end of the spindle and the nut 120, as well as, around the coupling end 41 of the flexible shaft. It will thus be seen that in the use of the self-aligning bearings 114—115 proper alignment of the tool spindle is maintained at all times. It will also appear that free high speed rotation of the spindle and tool will be provided. The nut 131 has an upwardly extending split and externally threaded sleeve 132, the upper end of which is bevelled, as seen at 133 and the coupling nut 39 of the flexible shaft 37 engages the bevelled portion to firmly compress the split end of the sleeve 132 upon the casing of the flexible shaft.

The stylus supporting member, in the construction shown, comprises a substantially cup-shaped casing 134 having a large milled nut or closure cap 135 at its upper end in which is threaded a rotary bushing 136 having a milled or ribbed nut portion 137 recessed to form a seat for a coil spring 138, which also seats upon the nut 135. This construction provides free adjustment of the stylus supporting spindle 139 in the casing. The lower end of the spindle 139 is enlarged as seen at 140 and this enlarged portion is freely slidable in a reduced bore 141 formed in the lower portion of the casing 134. The lower end of the spindle has a reduced sleeve portion 142 in which is mounted an elongated split tool supporting chuck 143 held in position by a milled nut 144 and clamped by this nut around the stylus 48 in adjustably supporting the stylus in the lower end of the spindle 139.

Between the end 140 and the bushing 136 a coil spring 145 is arranged upon the spindle and this spring permits quick raising of the stylus 48 out of engagement with the pattern by moving the key lugs 146 at the lower end of a milled nut 147, secured to the protruding end of the spindle 139, upwardly through apertures 148 formed in the under cut or grooved portion 150 of the bushing 136. This structure is more or less of a bayonet coupling. The lugs 146 normally engaging the grooved portion 151 of the bushing as indicated in Fig. 9 of the drawings, and by a slight rotation the lugs are brought into alignment with opposed recesses 148 and when in this position the spindle may be raised against the tension of the spring 145 and the spindle may be rotated to drop the lugs upon the upper end of the bushing. This will hold the stylus in a raised position.

It will be understood that while the members 40 and 49 are clamped in the casing portions 105 by compressing split winged parts 152 thereof, through the medium of bolts 153, note Fig. 12, the

other arm of the pantograph, for example the arm 45, is free to rotate around the member 49 above the point of attachment of the arm 44 therewith. It is also preferred that the casings 112 and 134 be of the same outside diameter, so that these members are interchangeable with the arms. In this way the routing tool may in some occasions, be located at the pivot between the arms 44 and 45 and the stylus supporting member arranged at the end of the arm 46. At this time, it will also appear upon a consideration of Figs. 1 and 2 of the drawings, that the pivot end of the arm 43 includes a casing portion 105 similar to these portions as provided on the arms 44 and 46; thus making it possible to interchange the parts and to change relative positions, thereof.

The casing 105 of the arm 43 is clamped around a tubular member 154, the latter being freely rotatable about a pin 155 adapted to be adjustably clamped in the slotted plate 50 in changing the pivot position of the arm 43.

As will appear from a consideration of Fig. 8 of the drawings, the upper end 48A of the stylus 48 is rounded, and by reversing the stylus in the holder, this rounded end may be used in guiding the tool in performing the rough cutting or routing after the outline of the pattern element has been carefully made. The rounded end of the stylus will keep the tool properly spaced from the fine definition in the resulting reproduction in the workpiece.

It will also be understood, that in certain instances, the spacing of figures or characters as appearing on the pattern element may be varied in the reproduction thereof, on the workpiece. For this reason, the fine adjustment is provided through the screw 83, the pica scale 156 being employed to gage picas and half picas, for example in the spacing of the characters MAY. As a matter of fact, by the two adjustments provided by the screw 75 and the screw 83, the pattern element may be shifted to entirely rearrange the subjects on the workpiece.

It will also be understood, that any type of pattern element can be used. In other words, printed or otherwise characterized sheets of paper or other material can have the characterizations thereof reproduced. In some instances, type or printed matter as appearing on a sheet of paper can be reproduced by simply oiling the paper, so that the printed matter will appear through the reverse side of the paper, this use being particularly desirable in the printing art. In other arts perspective reproductions can be made.

Having fully described my invention, what I claim as new and desire to secure by Letters Patent, is:

1. A machine of the character described comprising a standard, a table at the upper end of the standard, the upper surface of the table having a transverse recess extending throughout the full length thereof, a plurality of supporting plates adjustable longitudinally of said recess, means adjustably clamping a pattern element in two directions in one of said plates, means adjustably clamping a workpiece in another of said plates, a pantograph linkage comprising two pair of adjustably pivoted arms, means adjustably and pivotedly supporting one end of one of said arms upon the third of said plates, a stylus supporting body, a tool supporting body, said bodies being pivotedly coupled, one with one end of another of said arms and the other with adjacent ends of two other arms, and said bodies having handle members to guide the stylus and tool with

respect to said pattern element and said workpiece.

2. A machine of the character described comprising a standard, a table at the upper end of the standard, the upper surface of the table having a transverse recess extending throughout the full length thereof, a plurality of supporting plates adjustable longitudinally of said recess, means adjustably clamping a pattern element in two directions in one of said plates, means adjustably clamping a workpiece in another of said plates, a pantograph linkage comprising two pair of adjustably pivoted arms, means adjustably and pivotedly supporting one end of one of said arms upon the third of said plates, a stylus supporting body, a tool supporting body, said bodies being pivotedly coupled, one with one end of another of said arms and the other with adjacent ends of two other arms, said bodies having handle members to guide the stylus and tool with respect to said pattern element and said workpiece, and means extending longitudinally of said table for supporting said handle members.

3. A machine of the character described comprising a standard, a table at the upper end of the standard, the upper surface of the table having a transverse recess extending throughout the full length thereof, a plurality of supporting plates adjustable longitudinally of said recess, means adjustably clamping a pattern element in two directions in one of said plates, means adjustably clamping a workpiece in another of said plates, a pantograph linkage comprising two pair of adjustably pivoted arms, means adjustably and pivotedly supporting one end of one of said arms upon the third of said plates, a stylus supporting body, a tool supporting body, said bodies being pivotedly coupled, one with one end of another of said arms and the other with adjacent ends of two other arms, said bodies having handle members to guide the stylus and tool with respect to said pattern element and said workpiece, means extending longitudinally of said table for supporting said handle members, and a bearing plate on the upper surface of the table and an anti-friction bearing member supported at pivot ends of the first named arms in supporting the pantograph in its movement over the table.

4. A machine of the character described comprising a standard, a table at the upper end of the standard, the upper surface of the table having a transverse recess extending throughout the full length thereof, a plurality of supporting plates adjustable longitudinally of said recess, means adjustably clamping a pattern element in two directions in one of said plates, means adjustably clamping a workpiece in another of said plates, a pantograph linkage comprising two pair of adjustably pivoted arms, means adjustably and pivotedly supporting one end of one of said arms upon the third of said plates, a stylus supporting body, a tool supporting body, said bodies being pivotedly coupled, one with one end of another of said arms and the other with adjacent ends of two other arms, said bodies having handle members to guide the stylus and tool with respect to said pattern element and said workpiece, means extending longitudinally of said table for supporting said handle members, a bearing plate on the upper surface of the table and an anti-friction bearing member supported at pivot ends of the first named arms in supporting the pantograph in its movement over the table, and means comprising a foot treadle and a linkage coupled with said pantograph to assist

in the movement of the pantograph over the table of the machine.

5. A machine of the character described comprising a standard, a table at the upper end of the standard, the upper surface of the table having a transverse recess extending throughout the full length thereof, a plurality of supporting plates adjustable longitudinally of said recess, means adjustably clamping a pattern element in two directions in one of said plates, means adjustably clamping a workpiece in another of said plates, a pantograph linkage comprising two pair of adjustably pivoted arms, means adjustably and pivotally supporting one end of one of said arms upon the third of said plates, a stylus supporting body, a tool supporting body, said bodies being pivotally coupled, one with one end of another of said arms and the other with adjacent ends of two other arms, said bodies having handle members to guide the stylus and tool with respect to said pattern element and said workpiece, a flexible drive shaft, means for actuating said shaft, and means in the tool supporting body for coupling the flexible shaft with said tool.

6. A machine of the character described comprising a standard, a table at the upper end of the standard, the upper surface of the table having a transverse recess extending throughout the full length thereof, a plurality of supporting plates adjustable longitudinally of said recess, means adjustably clamping a pattern element in two directions in one of said plates, means adjustably clamping a workpiece in another of said plates, a pantograph linkage comprising two pair of adjustably pivoted arms, means adjustably and pivotally supporting one end of one of said arms upon the third of said plates, a stylus supporting body, a tool supporting body, said bodies being pivotally coupled, one with one end of another of said arms and the other with adjacent ends of two other arms, said bodies having handle members to guide the stylus and tool with respect to said pattern element and said workpiece, a vertical column protruding above the top of said table, a drive shaft supported at the top of said column, means involving an electric motor and relatively adjustable drives for actuating said drive shaft, and a flexible shaft for placing the drive shaft in operative engagement with said tool.

7. In a machine of the character described employing a pantograph linkage comprising two pair of pivotally and adjustably coupled arms, a table over which the pantograph is movable, means adjustable on the table providing a pivotal mounting for one of said arms, means at the free end of said arm for adjustably coupling the same with said first named means, a pattern element support adjustable on the table, two means adjustably securing an element in said support, a workpiece supporting member adjustable on said table, means adjustably retaining a workpiece in said member, and predetermined arms of the pantograph having means supporting a stylus for

operative engagement with said element and a tool for operative engagement with said workpiece.

8. In a machine of the character described 5 employing a pantograph linkage comprising two pair of pivotally and adjustably coupled arms, a table over which the pantograph is movable, means adjustable on the table providing a pivotal mounting for one of said arms, means at the 10 free end of said arm for adjustably coupling the same with said first named means, a pattern element support adjustable on the table, means adjustably securing an element in said support, a workpiece supporting member adjustable on said table, means adjustably retaining a workpiece in said member, predetermined arms of the pantograph having means supporting a stylus for operative engagement with said element and a tool for operative engagement with said workpiece, 15 and the ends of the arms engaging said last named means being of common structure, and two like handle members adjustably coupled with said arm ends in controlling the height of the stylus and tool with respect to said element and workpiece.

9. In a routing machine of the class described, a pantograph linkage for guiding a stylus and a tool in predetermined relation to each other, two elongated handle members, one for the stylus 20 and the other for the tool, a support over which said handle members are movable in the movement of said stylus and tool, and each handle member having means rotatably adjusting the same on its axis to raise and lower the handle member with respect to said support in raising and lowering the stylus and tool.

10. In a routing machine of the class described, a pantograph comprising two pair of elongated and longitudinally slotted arms, means adjustably coupling said pairs of arms, means including a stylus holder pivotally coupling one arm of each pair, an anti-frictional guide pivotally coupling the other arms, the free ends of the last mentioned arms being provided, one with 45 means forming an adjustable pivot on the machine, and the other with means for supporting a tool, means on the first named pivoted ends of the arms and the last mentioned arm end for supporting elongated handle members for axial rotation, and said last named means including means for adjusting the position of said handle members with respect to said last named means.

11. In a reproducing machine employing a pantograph controlling relative operation of a pattern tracing stylus and a workpiece forming tool, the combination with hand operated means for actuating said stylus and tool, of a treadle, a swivelled link pivoted directly to the pantograph, a link pivoted to the treadle, and a linkage supported on the machine coupling the first and second named links for placing the treadle in operative engagement with said pantograph.

ALBERT E. SCHNABLE.
